CLOCK HOUSING

Robert I. Kallman, Elburn, and Dominic J. De Fano, Palatine, Ill., assignors to Sunbeam Corporation, Chicago, Ill.

Filed June 30, 1972, Ser. No. 267,788

Term of patent 14 years

Int. Cl. D10—01

U.S. Cl. D42—7 R

Fig. 3.

Fig. 1.

Fig. 2.

Fig. 5.

Fig. 4.

Fig. 6.

FIG. 1 is a front elevational view of a Clock Housing showing our new design, the rear being substantially plain and unornamented;

FIG. 2 is a right side elevational view thereof, the left side being a mirror image thereto;

FIG. 3 is a top plan view thereof;

FIG. 4 is a bottom plan view thereof;

FIG. 5 is a sectional schematic view as taken from line 5—5 of FIG. 1, the internal structural details having been omitted as non-ornamental;

FIG. 6 is a fragmentary sectional schematic view as taken from line 6—6 of FIG. 1, the internal structural details having been omitted as non-ornamental.

We claim:

The ornamental design for a clock housing, as shown and described.
